H. G. WARR

RAIL ANCHOR

Filed Dec. 31. 1926

UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed December 31, 1926. Serial No. 158,251.

My invention relates to rail anchors and has for its general object the provision of an improved two-piece rail anchor device of the general type in which a clip member is driven into gripping engagement with one flange only of the rail base and is held in its operative position thereon by the cooperation of the other member of the device.

A more specific object of the invention is to provide an improved two-piece anchor of the above character, in which one member is adapted to be positioned to engage the rail base at one side only of the rail, and in which a clip member is adapted to be driven transversely of the rail into spring gripping engagement with one surface of the rail base and with said first mentioned member, the arrangement and construction of the parts being such that one of the parts of the device is subjected to a condition of maximum distortion before the clip member of the device reaches its operative position on the rail.

The invention has for further objects such other new and improved constructions of the parts of the device, whereby the parts will be maintained in firm operative engagement with each other and in tight gripping engagement with the rail base.

The invention is illustrated in two specific embodiments in the accompanying drawing wherein

Fig. 1 is a side view of one embodiment of the invention showing the parts in their operative position on one flange of a rail base.

Fig. 2 is a sectional view taken on line 2-2 of Fig. 1 illustrating the manner in which one of the members takes a biting hold on the rail base and showing also the construction whereby an interlocking engagement is effected between the members to prevent movement of one member with relation to the other longitudinally of the rail.

Fig. 3 is a view in perspective of the clip member forming a part of the embodiment shown in Figs. 1 and 2.

Fig. 4 is a view in perspective of a wedge member employed in the above embodiment, and

Fig. 5 is a view similar to Fig. 2, but showing a modified form of the invention.

The embodiment of the invention shown

in Figs. 1 to 4, inclusive, of the drawing consists of a wedge member 10 which is preferably, though not necessarily positioned to bear against the bottom surface 11 of the rail base, and a clip member 12 which embraces both the wedge and the base flange of the rail. The surface 13 of the wedge member bears against the base flange of the rail and is formed along its side edges with a plurality of angular shaped teeth 14 adapted, when the wedge is in its applied position, to bite into the surface of the rail base engaged. The opposite side 15 of the wedge inclines inwardly toward the center of the rail when in its normal applied position. Preferably, the inclination of the surface 15 is slightly greater, with respect to the horizontal, than the inclination of the top surface of the rail base. The said inclined surface 15 merges at the thick portion of the wedge with a curved end surface 16. The end of the wedge is provided also with lugs 17 and 18 adapted to engage with the longitudinal corner portion of the rail base, so as to hold the wedge against inward movement on the base flange when the clip is being driven to its applied position. The teeth 14, biting into the surface of the rail base, prevent movement of the wedge outwardly.

The clip member is made, preferably, from a piece of spring metal, rectangular in cross section and is bent to substantially U-shaped configuration to provide upper and lower jaws 19 and 20. The upper jaw is formed with a relatively long bearing surface which bears flat against the upper surface of the rail base. The lower jaw 20 is so formed that, when in its applied position, it bears flat against the inclined surface of the wedge 10. The distance between the jaws 19 and 20 is normally less than the combined thickness of the base flange of the rail and the wedge at the points engaged, whereby the jaws are spread apart and exert a firm spring grip when in their applied position. The inclined surface of the wedge, being at a slightly greater angle than the top surface of the rail base, brings the point of maximum combined thickness of the base flange and wedge at a point near the edge of the base flange. With such construction, the clip is driven through a condition of

maximum distortion and the tension is slightly relieved before the clip reaches its applied position.

In order to provide an interlocking engagement between the clip and the wedge, I preferably form the lower jaw of the clip with a recess 21, which receives a central rib 22 formed on the under surface of the wedge. The extreme end of the clip is preferably 10 tapered, as shown at 23, to provide cam surfaces which, together with the curved surface of the wedge facilitates the application of the device to the rail.

In operation, the wedge may be positioned 15 on either the bottom or top surfaces of the rail base, with the lugs 17 and 18 abutting against the longitudinal edge of the rail base. The clip is then driven transversely of the rail into gripping engagement with 20 the inclined surface of the wedge and one surface of the rail base. The spring tension to which the clip is subjected in driving it to its applied position, forces the teeth 14 of the wedge into the surface of the rail 25 base so as to prevent movement of the wedge in a direction to loosen the grip of the clip. The outward movement of the clip is resisted by reason of the resiliency of the clip and the difference in angle of the inclined upper 30 surface of the rail base and the inclined surface 15 of the wedge.

In Fig. 5 I have illustrated another embodiment of the invention, in which the wedge member instead of being provided 35 with the central rib 22 is formed on its bottom surface with side flanges 24-24 which fit over the opposite side faces of the clip. The clip member shown in the modified construction is the same as that shown in the 40 preceding figures except that the central groove 21 is omitted.

I claim:

1. A rail anchor comprising a wedge shaped member adapted to engage the base 45 flange of a rail, and a clip formed with upper and lower jaws adapted to be driven transversely of the rail into gripping engagement with a surface of said rail base and with said wedge member; the angle of said 50 wedge being such relative to the inclined top surface of the rail base that the clip is driven through a condition of maximum distortion before it reaches its applied position.

2. A rail anchor comprising a wedge shaped member adapted to engage the base 55 flange of a rail, and which, when in its operative position, decreases in width toward the center of the rail, and a clip member adapted to be driven transversely of the 60 rail into gripping engagement with a surface of said rail base and with said wedge member.

3. A rail anchor comprising a wedge shaped member adapted to engage the base 65 flange of a rail and formed with a surface

inclinining inwardly at a greater angle than the inclined surface of the rail base, and a clip formed with upper and lower jaws adapted to be driven transversely of the rail into gripping engagement with a surface of 70 said rail base and of the inclined surface of said wedge member.

4. A rail anchor comprising a wedge shaped member adapted to engage the base 75 flange of a rail at one side only of the rail base, and a clip formed with upper and lower jaws adapted to be driven transversely of the rail into gripping engagement with a 80 surface of the said rail base and with said wedge member.

5. A rail anchor comprising a wedge member adapted to bear against one surface of a rail base flange at one side only of the rail and which decreases in width toward the center of the rail, and a spring clip, the 85 jaws of which are spread apart when in its applied position, to effect a spring grip on one surface of the rail base and a surface of said wedge member; the angle of said wedge being such relative to the inclination 90 of the top surface of the rail base that the clip is driven through a condition of maximum distortion before it reaches its applied position.

6. A rail anchor comprising a wedge member formed on one surface with teeth adapted to be pressed into one surface of a rail base at one side of a rail, and a spring clip formed with jaws adapted to embrace the base flange of the rail and the said wedge. 95

7. A rail anchor comprising a wedge member formed on one surface with teeth adapted to be pressed into biting engagement with one surface of a rail base at one side of a rail and provided at one end with means for abutting against the longitudinal edge of the rail base, and a spring clip formed with jaws adapted to be driven transversely of the rail into spring gripping engagement with the rail base and said wedge. 100

8. A rail anchor comprising a wedge member formed on one surface with teeth adapted to be pressed into biting engagement with one surface of the rail base at one side only of a rail and provided at one end with means for abutting against the longitudinal edge of the rail base, and a spring clip formed with jaws adapted to embrace the base flange of the rail and the said wedge; the inclination of the wedge being such that the combined thickness of the rail base and said wedge is greatest near the edge of the rail base, whereby the clip is driven through a condition of maximum distortion in its 115 movement transversely of the rail to its applied position.

9. A rail anchor comprising a wedge member which decreases in thickness toward the center of the rail, formed on one surface with teeth adapted to take a biting hold on 120

125

the rail base to prevent outward movement of the wedge and provided at one end with means for engaging with the edge of the rail base to prevent inward movement of the wedge, and a spring clip member adapted to be driven transversely of the rail into gripping engagement with the rail base and said wedge; one of said members being formed with means providing an interlocking engagement with the other member.

10. A rail anchor comprising a wedge member which decreases in thickness toward the center of the rail, formed on one surface with teeth adapted to take a biting hold on the rail base to prevent outward movement of the anchor and provided at one end with means for engagement with the edge of the rail base to prevent inward movement of the wedge, and a spring clip member adapted to be driven transversely of the rail into gripping engagement with the rail base and said wedge; one of said members being

formed with a rib adapted to enter a groove formed in the other, to provide an interlocking engagement of the wedge and clip. 25

11. A rail anchor comprising a wedge member which decreases in thickness toward the center of the rail, formed on one surface with teeth adapted to take a biting hold on the rail base to prevent outward movement of the wedge and provided at one end with spaced lugs for engagement with the edge of the rail base to prevent inward movement of the wedge, and a spring clip member adapted to be driven transversely 30 of the rail into gripping engagement with the rail base and said wedge; the inclination of the wedge being such, with relation to the top surface of the rail base that the jaws of the clip are spread apart when 35 moved from their applied position in a direction to remove the anchor from the rail. 40
